UNITED STATES PATENT OFFICE.

LUTHER J. SEVISON, OF CONSTANTINE, MICHIGAN, ASSIGNOR TO FAWN RIVER MANUFACTURING COMPANY, OF CONSTANTINE, MICHIGAN, A CORPORATION OF MICHIGAN.

MAGNETO.

1,266,063.

Specification of Letters Patent. Patented May 14, 1918.

Application filed August 10, 1908. Serial No. 447,818.

To all whom it may concern:

Be it known that I, LUTHER J. SEVISON, citizen of the United States, residing at Constantine, in the county of St. Joseph and 5 State of Michigan, have invented certain new and useful Improvements in Magnetos, of which the following is a specification.

This invention relates to an improvement in high tension ignition systems for gas engines and the like and more particularly to 10 an improvement in magnetos designed for use in connection for such systems, and the primary object of the invention is the provision of a magneto of the alternating current type designed to effect the ignition of 15 gas or gasoline motors without the use of batteries, vibrators, spark coils or complicated wiring.

A further object of the invention is the 20 provision of a device of this character of the alternating type, in which the circuit to the plugs is closed only when the sparks are to be produced, said circuit being at all other times open.

25 A further object of the invention is the provision of a device of this character of the alternating type in which the current from the armature is continuously delivered to the condenser and the current from the armature and condenser is periodically unloaded on to the primary of the spark coil 30 just at the point of alternation, when the armature is rotating at low speed, so that it is possible to obtain a high wave spark at 35 low speed.

A further object of the invention is the provision of a device of this character with 40 which a high wave spark can be obtained at low speed and which is provided with means for maintaining the voltage constant regardless of the speed of the armature shaft.

A further object of the invention is the provision of improved timer mechanism for advancing and retarding the spark and 45 changing the relation of the armature to the timing mechanism which distributes the current to the motor, and for producing an initial spark to start the motor.

Other objects of the invention will be apparent from the detailed description herein- 50 after when read in connection with the accompanying drawings forming a part hereof, wherein a preferable embodiment of the invention is shown and wherein like nu-

merals of reference refer to similar parts in 55 the several views.

In the drawings,

Figure 1 is a longitudinal section of the magneto,

Fig. 2 is an end elevation, with a portion 60 of the frame removed showing the circuit closing means employed for periodically unloading the current from the armature and condenser on to the primary of the spark coil,

Fig. 3 is an end elevation of the opposite 65 end of the magneto, with a portion of the frame removed, showing the distributor arm and the spark plug contacts,

Fig. 4 is a diagrammatic view illustrating 70 the wiring between the magneto and the spark coil and plugs,

Fig. 5 is a sectional view of the timer box and gearing, and

Figs. 6 and 7 are detail views.

Referring now more particularly to the drawings, the magneto comprises a suitable frame in which are mounted heavy permanent magnets A of any suitable form and construction, which are provided with soft 80 iron field pieces a between which is adapted to rotate the armature B. The armature B is of the usual shuttle pattern and extending from the ends thereof are shafts B' and B'', which are journaled in end plates of any 85 suitable construction which form a part of the frame of the machine, and project outwardly therebeyond. Secured within the shaft B'' of the armature so as to rotate therewith is a rod or conductor b, which 90 is formed of copper or other good conducting material and which is insulated from the shaft B'' by a sleeve of insulating material b' which extends substantially the entire length thereof. The conductor b terminates at its 95 outer end in a button b'' which is of substantially the same diameter as the end of the shaft B'' and said button is insulated from the end of the shaft by a flange on the end of the insulating sleeve b'. The outer face 100 of the button b'' is provided with a centrally disposed depression therein for a purpose to be hereinafter set forth. The armature B is provided with a single winding of coarse wire, one end of which is grounded to the 105 armature frame and the other end of which is electrically connected in any suitable manner to the inner end of the rod or conductor

b heretofore referred to. Secured within the frame of the machine above the armature *B*, so as to be readily accessible for the purpose of removal is the condenser *C* which may be 5 of any suitable construction. One terminal of the condenser is grounded to the frame of the machine and the other terminal of the condenser is electrically connected to a metallic arm *D* which projects from one end of 10 the frame of the machine and is positioned directly over the projecting end of the shaft *B*² heretofore described. The arm *D* is secured to and insulated from the frame of the machine in any suitable manner and terminates 15 at its outer end in a binding post *d* upon which is adapted to be threaded the usual clamp nut. Depending from the outer end of the arm *D* and in electrical connection therewith is a leaf spring *D'*, the lower 20 end of which is provided with a cup-like portion *d'*, in which is secured a carbon button *d*² which is adapted to be held in yieldable engagement with the outer end of the copper rod *b* heretofore referred to. The 25 outer face of the carbon button *d*² is flat so as to make a good contact with the button *b*² on the end of the rod or conductor *b* and is provided with a slot therein which extends transversely thereacross. By this construc- 30 tion the faces of both the carbon button *d*² and copper button *b*² wear away equally at all points so that a perfectly flat contact is at all times maintained between them. Secured to one end of the frame of the machine 35 and extending outwardly therefrom below and on opposite sides of the extended portion of the armature shaft *B*² are two metallic arms *E* *E*, the inner ends of which are secured to and insulated from the frame of the 40 machine in any suitable manner. The arms *E* *E* are provided intermediate their ends on the outer sides thereof with contact studs *e* *e* and terminate at the outer ends thereof in binding posts *e'* *e'* which are 45 adapted to be connected with one terminal of the spark coil, as will be hereinafter more particularly set forth. Depending from opposite sides of the arm *D* are two leaf springs *F* *F*, the upper ends of which are 50 connected in any suitable manner to the arm *D* so as to be in electrical connection therewith and the lower ends of which are provided on the inner sides thereof with contact studs *f* *f*, which are adapted when the 55 springs are permitted to assume their normal position, to engage the contact studs *e* *e* carried by the arms *E* *E* heretofore referred to. Secured to the projecting end of the armature shaft *B*' so as to rotate therewith 60 but insulated therefrom, is an eccentric cam *G* which lies between the springs *F* *F* and said springs are provided intermediate the ends thereof with blocks *f'* *f'* which are held in yieldable engagement with the periphery of the cam. The periphery of the 65

cam is formed with one high portion and one low portion which is connected to the high portion by an abrupt shoulder *g*, the periphery of the cam being curved gradually from the low portion to the high portion thereof. 70 From this construction it will be noted that during the revolution of the armature shaft the contact *f* of either of the springs *F* will only be permitted to contact with the contact *e* on the adjacent arm *E* when the block *f'* 75 carried by such spring rests on the low portion of the eccentric cam. It will thus be seen that during one revolution of the cam *G*, each of the springs *F* will be once permitted to assume a position whereby the contact *f* carried thereby will for a short period of time only engage the contact *e* on the adjacent arm *E*. When the armature is rotating at slow speed and one of the blocks *f'* of the springs *F* rides off of the high portion 80 of the cam, the contact *f* carried thereby will contact with the contact *e* on the adjacent arm *E* before the cam has traveled any substantial distance and the parts are so constructed and arranged that the contacts *E* 85 and *F* will be brought together and close the circuit to the primary coil of the spark coil just when the armature has reached the highest potential or is passing out of the field; thus the high wave spark is used even 90 at low speed. When the armature is rotating at a higher speed, however, it will be obvious that the contacts *E* and *F* will not be brought together until the armature has traveled a greater distance than when rotating 95 at low speed, since the speed of rotation of the cam has been increased and the time required for the spring to move from the high point of the cam to a position permitting the engagement of the contacts *e* and *f* 100 is always the same, so that when the device is rotating at high speed the spark is made later in the revolution of the armature and the high wave is not caught and the voltage remains the same as when the machine is rotating at a low speed. It will thus be seen 105 that the construction of the circuit closing devices is such that the voltage of the current generated will always be constant regardless of the speed of rotation of the armature. The cam *G* is preferably adjustably mounted upon the shaft *B*' so that by shifting the position of the same the voltage can be varied to any desired extent. The 110 several parts of the circuit closer are preferably inclosed by a casing *G'* of any suitable construction which is secured to the end frame of the machine in any suitable manner and is provided with apertures therein to permit the binding posts *d* and *e'* *e'* to pass 115 therethrough, said binding posts being of course insulated from said casing. The end of the frame of the machine in 120 which the armature shaft *B*' is journaled is provided with an integral journal box to 125

afford an adequate bearing for said shaft and also to form a support for the timer casing or box to be hereinafter described. The timer box comprises a hollow casing 5 H, from the opposite sides of which extend hubs h and h', the hub h fitting loosely upon the journal box on the frame in which the shaft B' rotates, and said journal box is provided on the exterior thereof with an 10 annular groove into which projects a set screw h² carried by the hub h. From this construction, it will be apparent that while the timer box is so secured to the frame that it cannot be disengaged therefrom, it may be 15 shifted therearound and any suitable means may be employed to impart such a movement thereto, the upper end of said box being preferably provided with an ear or offset portion to which is adapted to be 20 connected a suitable actuating lever so that the operator can readily shift the timer box. Any suitable means may be provided for locking the timer box in any desired position of adjustment and the means employed in the present embodiment of the 25 invention for such purpose is a segmental rack H' which is secured to the end frame of the machine adjacent the timer box and which is adapted to be normally engaged 30 by a spring actuated pawl H², which is carried by the timer box and is of such a construction that the timer box may be readily shifted in either direction. Carried by the timer box and fixedly secured 35 thereto is a counter shaft I upon which are loosely mounted two gears K and L which are connected so as to rotate together, the gear K meshing with a gear M which is rigidly secured to the armature shaft B', 40 and the gear L meshing with a gear N, which is carried by a sleeve N' which rotates loosely on the armature shaft B' and projects through the hub h' of the timer box and is adapted to be geared in any suitable 45 manner to the motor shaft so as to be rotated thereby. In the form of the invention illustrated in the present application, the gear K is twice the size of the gear M with which it meshes, while the 50 gears L and N are of the same size, so that it will be seen that for each revolution of the sleeve N', the armature will be revolved twice, but, as it is essential that the armature travel at motor speed, the gearing 55 between the motor and sleeve N' should be such that the sleeve is rotated only once during every two revolutions of the motor shaft. It will be understood, however, that the relative sizes of the gears is subject to 60 modification depending upon the number of cylinders to the motor. Rigidly supported along side of the timer box H by means of a bracket or arm extending from the frame of the machine, is a plate O formed of any 65 suitable insulating material, said plate being

provided with a circular aperture therein which constitutes a bearing for the hub h' of the timer box. Embedded in or otherwise secured to the outer face of the plate O are a plurality of segmental contact plates 70 o, which are arranged an equal distance apart and circumferentially of the sleeve N', there being one such contact plate provided for each cylinder of the motor. The segmental contact plates o are each connected by suitable wiring with binding posts o' which are secured to the upper portion of the plate o and are adapted to be connected to the spark plugs in the cylinders of the motor, said binding posts being each provided with a clamp nut of any suitable construction. Embedded in or otherwise secured to the outer face of the contact plate O within and concentrically of the segmental contact plates o is an annular contact plate 75 o² which is connected to a binding post o³, which is secured to the upper portion of the plate O and is adapted to be connected by suitable wiring to one of the terminals of the secondary coil of the spark coil. Rigidly secured to the sleeve N' so as to rotate therewith just outside of the plate O is a distributor arm P, which upon rotation of the sleeve is adapted to successively make an electrical connection between the several 80 segmental contact plates o and the annular contact plate o². The distributor arm P comprises an arm p of insulating material which is keyed or otherwise rigidly secured to the sleeve N' and a metallic leaf spring 100 p', which is secured to and projects laterally from the free end of said arm. Carried by the outer end of the leaf spring p' is a contact block p² which is always held by said spring in yieldable engagement with the outer surface of the plate O. The contact block p² is provided with two bearing portions extending from the face thereof, one of which is adapted to continuously engage the annular contact ring o² and the other of which is adapted upon the rotation of the distributor arm to successively sweep across the segmental contacts o. The distributor arm P is preferably inclosed by a 105 casing, which is of any suitable construction and is secured in any suitable manner to the outer surface of the plate O, said casing being provided with a centrally disposed opening therein to permit the sleeve N' and shaft B' to pass therethrough. 110 In the operation of the device as heretofore described, which is intended for use in connection with motors of four cylinders, the sleeve N' is connected by gearing of any suitable construction to the motor 125 shaft so that it will be rotated once during every two revolutions of the shaft. It will be understood, however, that this gearing will be varied according to the type of motor with which the device is used. The 130

binding posts e' e' at the ends of the arms E E are connected by suitable wiring to one terminal of the primary of a spark coil Q which may be of any well known type, the other terminal of the primary being grounded to the frame of the magneto; the binding posts o' are connected by suitable wires to the plugs in the cylinders of the motor; and the binding post o^3 is connected 10 by a suitable wire or conductor to the secondary of the spark coil.

From the above construction, it will be noted that the condenser is in circuit with the winding of the armature during its full travel and when the armature travels through its fields, the armature winding loads, and so does the condenser. One terminal of the primary of the spark coil is connected to the binding posts e' e' , while 15 the other terminal of the primary is grounded on the base of the machine, and as the condenser and armature are always in connection with the bar D which carries the springs F F , it will be apparent that when 20 either of the springs is permitted by the cam G which is positioned therebetween to move a sufficient distance to close the circuit through contacts f , e , the armature and condenser instantly unload direct onto the 25 primary of the spark coil, where the current is induced in the secondary of the spark coil and thence conducted to the distributor and the plug. The closing of the circuit to the primary of the spark coil is 30 controlled by the cam G and the springs F F , which as has been heretofore pointed out are of such construction that when the device is running at low speed the current 35 will be taken on the high wave and the voltage will remain constant at all speeds. 40

It will be noted that the sparking circuit is open during the greater part of the travel of the magneto which renders the magneto much easier to drive than the closed circuit 45 machine heretofore in use.

The spark may be advanced or retarded any desired extent by shifting the timer box, and it will be apparent that as the mechanism heretofore described for 50 periodically closing the circuit operates entirely independent of the timer box, the character of the spark produced is the same at all times whether sparking the motor early or late in the stroke.

55 As the distributor arm travels, in the form illustrated in the drawings, at one half motor speed, the sparking or timing range, on the fly wheel, is equal to twice the length of the segmental contact plate 60 on the plate O . With this wide range, a full throw of the timer box H will revolve the armature one-half turn when the motor is idle, thus the operator can start the motor by merely manipulating the timer 65 box, provided of course the motor is charged

with gas. As owing to the fact that with the particular type of circuit closer employed, the high wave spark is delivered when the device operates at low speed, the magneto can be relied on to start the motor at a very slow turn of the crank; in fact the crank may be turned very slowly until the motor is charged with gas, when to start the same it is only necessary to quickly shift the timer box. 70

While the device is particularly designed for use in ignition systems which do not employ batteries, it is so constructed that batteries may be used if desired, the battery wires when used being connected to 80 the binding post d and to the spark coil, as shown in the diagrammatic view illustrated in Fig. 4, and an ordinary two throw switch being provided for cutting out the magneto and throwing in the battery. 85

While a preferred embodiment of the invention is illustrated in the drawings, it will be appreciated that the invention is not necessarily limited to the exact construction therein shown, as many changes 90 and alterations may be made thereto without departing from the spirit of the invention.

Having thus described the invention, what I claim as new and desire to secure by 95 Letters Patent is:

1. In an ignition apparatus, a magneto provided with an armature, a condenser continuously in circuit with said armature winding, a spark coil, a normally open circuit between the primary of the spark coil and the armature winding and condenser, and a circuit closer interposed in said circuit. 100

2. In an ignition apparatus, an alternating current magneto, a condenser continuously in circuit with the armature winding of said magneto, a spark coil, a normally open circuit between the primary of the spark coil and the armature and condenser, 110 a circuit closer interposed in said circuit, and means actuated by the armature for intermittently closing said circuit. 105

3. In an ignition apparatus, an alternating current magneto, a condenser continuously in circuit with the armature winding of said magneto, a spark coil having its primary in a normally open circuit with said condenser and armature winding, and a circuit closer in said circuit adapted to be intermittently actuated by said armature at low speed to permit the current to unload from the armature and condenser on to the primary at the highest potential of the armature. 115

4. In an ignition apparatus, an alternating current magneto, a condenser continuously in circuit with the armature winding of said magneto, a spark coil having its primary in a normally open circuit with said 120

condenser and armature, and a circuit closer in said normally open circuit adapted to be intermittently actuated by the armature of the magneto, the time of actuating of said circuit closer being automatically varied according to the speed of rotation of said armature.

5. In an ignition apparatus, a magneto, a condenser continuously in circuit with the 10 armature winding of said magneto, a spark coil having its primary in a normally open circuit with said condenser and armature, a circuit closer interposed in said circuit adapted to be intermittently actuated by 15 said armature, and a plurality of ignition devices arranged in circuit with the secondary of the spark coil:

6. In an ignition apparatus, a magneto, a condenser continuously in circuit with the 20 armature winding of said magneto, a spark coil having its primary in a normally open circuit with said condenser and armature, a circuit closer in said normally open circuit adapted to be intermittently actuated by the 25 armature, a plurality of ignition devices, and means actuated by the armature for successively placing said ignition devices in circuit with the secondary of the spark coil.

7. In an ignition apparatus, a magneto, a condenser continuously in circuit with the 30 armature winding of said magneto, a spark coil, a normally open circuit between the armature, condenser, and primary of the spark coil, a circuit closer in said circuit adapted to be intermittently actuated by the 35 armature, a plurality of ignition devices, and means adjustable independently of said first mentioned circuit closer for successively placing said ignition devices in circuit with the secondary of the spark coil.

8. In an ignition apparatus, an alternating current magneto, a condenser continuously in circuit with the armature winding of said magneto, a spark coil having its primary in a normally open circuit with the 45 armature and condenser, a movable contact member in said normally open circuit, and a cam carried by the armature and engaging said movable contact member.

50 9. In an ignition apparatus, a magneto, a condenser continuously in circuit with the armature winding of said magneto, a contact point adapted to be connected to the primary of an induction coil, a spring actuated arm in electrical connection with the armature winding and condenser and adapted in its normal position to engage said contact point, and a cam carried by the armature and normally engaging said 55 spring actuating arm to hold the same away from said contact point.

10. In an ignition apparatus, a magneto, a condenser continuously in circuit with the armature winding of said magneto, a 60 pair of contact points adapted for connec-

tion to a sparking circuit, a pair of spring actuated circuit closing arms in electrical connection with the armature winding and condenser and adapted to coöperate with said contact point, and a cam carried by 70 the armature shaft and normally engaging said spring actuated arms to hold the same away from said contact points.

11. In an ignition apparatus, a magneto comprising a frame, an armature journaled 75 in said frame, a condenser in said frame, an arm extending from said frame and electrically connected with one of the terminals of said condenser, the other terminal of said condenser being grounded, a connection between said arm and one terminal of the armature winding, the other terminal of said winding being grounded, a contact carried by the frame and adapted to be connected to a sparking circuit, a movable contact member carried by the arm projecting from the frame and adapted to coöperate with said contact point, and a cam carried by the armature shaft and normally engaging said movable contact 85 member to hold the same away from said contact point.

12. In an ignition apparatus, a frame, a magneto having its armature journaled in 95 said frame, a rod of conducting material carried by the armature shaft and insulated therefrom, said rod being connected at its end to the armature winding and provided at its outer end with a contact portion, a condenser mounted in the frame, an 100 arm extending from the frame and electrically connected to one terminal of said condenser, a spring secured to said arm and yieldably engaging the contact portion of the conductor rod carried by the 105 armature shaft, a pair of contact points adapted to be connected to the primary of a spark coil, a pair of spring arms secured to the arm extending from the frame and provided with contact points adapted to 110 coöperate with said first mentioned contact points, and a cam carried by the armature shaft and positioned between said spring arms.

13. In an ignition apparatus, a frame, a 115 magneto provided with a rotatable armature journaled in said frame, a conducting member carried by the armature shaft and electrically connected to the armature winding, a condenser mounted in the frame, a 120 spring arm electrically connected to one terminal of said condenser and provided with a carbon brush yieldably engaging the conducting member carried by the armature shaft, said brush being provided with 125 a transverse slit in the face thereof.

14. In an ignition device, a frame, a magneto provided with a rotatable armature journaled in said frame, a conducting member carried by the armature and elec- 130

trically connected to the armature winding, a condenser mounted in the frame, an arm extending from the frame and electrically connected to one terminal of said condenser, 5 a spring secured to said arm and yieldably engaging the conducting member carried by the armature shaft, a contact point adapted to be connected to the primary of a spark coil, and means actuated by the

armature for intermittently closing the circuit between the arm on the frame and said contact point. 10

In testimony whereof I affixed my signature in presence of two witnesses.

LUTHER J. SEVISON.
